CHECKER FOR BLAST FURNACE STOVES

James E. MacDonald, Pittsburgh, Pa.

Application March 2, 1935, Serial No. 9,051

2 Claims. (Cl. 263—51)

My invention relates to checker structures that are particularly suitable for use with blast furnace stoves, but which can also be employed with open hearth and other furnaces.

5 In the building of checker work of the class referred to, bricks of rectangular form have been frequently employed, but because of their flat surfaces, they cannot absorb and give off heat as rapidly as structures wherein the gas-contacting surfaces of the bricks are of non-planular form, and have what, in effect, are projections that will become heated quickly to high temperatures by the hot gases, and which will give off heat rapidly when the direction of flow through 10 the checker work is reversed.

15 While bricks having gas-contacting faces of irregular form have heretofore been made, they have been expensive to manufacture, and in some cases, cause excessive turbulence by creating cross currents of the gases, so as to greatly reduce the velocity of the air or gas. Separately-formed 20 inserts have also been placed in the flues formed by the bricks, but these have been expensive to manufacture and require much extra cost in handling and laying. Furthermore, the inserts themselves tend to prevent the gas and air flowing 25 at the desired velocities.

30 One object of my invention is to provide checker work having bricks of such form that they can be set up with substantially the same facility as ordinary rectangular bricks, but which nevertheless have ribs or similar projections formed thereon in such manner that they can be manufactured at little or no greater expense 35 than ordinary rectangular bricks.

35 Another object of my invention is to provide 40 bricks having projections that will be very effective in the absorption of and the giving off of heat, and which will nevertheless not unduly interfere with free movement of air and gas through the checker-work, and wherein the projections will assist in properly aligning the bricks during building of the checker work, and will also assist in maintaining the bricks in position.

45 Another object of my invention is to provide 50 specially-formed bricks that can be readily assembled to form graduated flue areas, and wherein there are no flat surfaces or offsets upon which deposits may readily accumulate, but wherein a desired degree of turbulence on the gas or air stream is effected to cause various portions thereof to come into contact with the heating surfaces of the brick.

55 Still another object of my invention is to provide checker bricks of such form that they have

maximum area for supporting vertical loads, and which can conveniently be reclaimed when replacing checker work.

Some of the forms which my invention may take are shown in the accompanying drawing 5 wherein Figure 1 is a vertical sectional view through a blast furnace stove; Fig. 2 is a view taken on the line II of Fig. 1; Fig. 3 is an enlarged plan view of one of the bricks of Fig. 2; Fig. 4 is a view taken on the line IV of Fig. 1; 10 Fig. 5 is an enlarged plan view of one of the bricks of Fig. 4; Fig. 6 is a view taken on the line VI of Fig. 1; Fig. 7 is an enlarged view of one of the bricks of Fig. 6; Fig. 8 is a view taken on the line VIII of Fig. 1; Fig. 9 is an enlarged 15 plan view of one of the bricks of Fig. 8; Fig. 10 is a face view showing the general appearance of one of the bricks of Figs. 4 to 9; Fig. 11 represents plan and face views of a modified form of brick; Fig. 12 represents plan, face and edge 20 views of still another form of brick; Fig. 13 shows plan, face and edge views of a further modification, and Fig. 14 is a sectional view showing still a further modification.

As shown in Fig. 1, the checker bricks are 25 arranged in four zones—the bricks of Figs. 8 and 9 appearing in the lowermost or first zone, and the bricks of Figs. 6 and 7 appearing in the next or second zone—the bricks of Figs. 4 and 5 appearing in the third zone, and the fourth and 30 uppermost zone being composed of the bricks of Figs. 2 and 3. It will be noted that the cross-sectional areas of the flues are of gradually reduced diameter from the top to the bottom of the checker chamber, so that as the hot gases 35 flow down through the checker work and become cooled through absorption of heat by the checker bricks, the lessening in volume of the gases will be substantially in accordance with the reduction in flue area as between successive sections. 40 The gases when they reach the bottom series of checker bricks will, of course, be considerably cooled, and not require so much flue area.

Conversely, when cold air or gases enter the bottom of the checker chamber, they will absorb 45 heat from the checker brick and expand during their upward travel. By this arrangement, a proper velocity of the air or gas and effective contact thereof with the bricks will be maintained.

The bricks 16 of Figs. 2 and 3 may be of plain 50 rectangular form, and all of substantially the same size. The bricks 17 which form the next zone have two pairs of ribs 18 formed on each side thereof, and extending vertically approxi-

mately the full lengths of the bricks, although they may be tapered or beveled at their upper ends, so that the upper ends of such bricks will have their side faces flush with the side faces of the bricks 16. Also, the upper edges of the top-most course of bricks 16 may be bevelled or of wedge shape in order to eliminate flat surfaces on which dirt and other deposits could accumulate.

10 The vertical mid portions of the bricks 17 are flat, so as to provide seating surfaces for the edges of the adjacent bricks, as shown at 19. The ribs at either side of the said flat surfaces assist in retaining the abutting bricks in position, 15 and facilitate the laying of the bricks in proper alignment.

The bricks 21 of Figs. 6 and 7 constitute the second zone of the checker chamber, while the bricks 22 of Figs. 8 and 9 are employed in the 20 bottom zone of the checker chamber. The bricks 21 and 22 are of the same general form as the bricks of Fig. 4, but have their ribs of greater thickness and width, so as to effect the desired changes in effective flue area, as above-explained.

25 The bricks of the various courses may be of any suitable length in vertical directions, and a desired number of horizontal courses of each size of bricks may be laid, depending upon the vertical length of zone required.

30 The checker work is supported on arches 24, and rider bars 25 which may be of any suitable well-known form are provided, the bars being of a thickness corresponding approximately to the thickness of the checker bricks and placed so as 35 to not obstruct the flue passages.

The vertical ribs 18 of the various bricks form vertically-extending recesses or grooves that produce some turbulence in the gas stream, causing all portions of the stream to be brought into 40 direct contact with the bricks, without too greatly retarding the flow of the gases. Also, they readily absorb and give off heat and present a much wider flue area for contacting the gases than if the flue openings were of rectangular form in 45 cross section.

For example, in the case of the bottom zone, and with bricks of a given size, if the flue openings were of rectangular form as in Fig. 2, having the same horizontal dimensions as the overall 50 horizontal dimensions of the flues of Fig. 8, there would be but 16 square inches of brick surface exposed to the gas surface per flue, as against 22 square inches with the ribbed bricks 22 of Fig. 8.

In other words, the area of the walls as in 55 Fig. 8 is 37½% greater per flue than the wall area in Fig. 2. The percentages of increase in flue wall area in Figs. 4 and 6 as compared to Fig. 2 is, of course, not so great as in Fig. 8, because the ribs of Figs. 4 and 6 are shallower than 60 in Fig. 8.

In actual practice, the cross-sectional area of the flue openings in the zone 1 (the bottom zone) may be nine square inches; the cross-sectional area in zone 2 may be 12 square inches; the cross-sectional area in zone 3 may be 14 square inches, and the cross-sectional area of the flue openings in zone 4 (the top zone) may be 16 square inches. The effect of this variation in cross-sectional area as between the different zones is to give 65 graduated flue passages as above-explained, to compensate for expansion and contraction of the gas and air passing through the checker-work.

The bricks of Figs. 4 to 10 can be produced at a manufacturing cost not greatly in excess of producing the plain-faced bricks of Fig. 2, in that they can be formed by extrusion through suitable dies that are ribbed or grooved to produce 5 the ribs on the faces of the bricks.

Referring now to Fig. 11, I show a brick 27 which is somewhat similar to the bricks of Figs. 4 to 10, but having the larger curved ribs 28 instead of the narrow ribs 18. The flat areas 29 10 intermediate the ribs 25 will be engaged by the edges of adjacent bricks and the ribs not only provide greater contacting area for the gases and air, but serve to align and support the brick, as in the other figures.

In Fig. 12, the bricks 31 have protuberances or ribs 32 extending crosswise of the bricks. These ribs serve to give increased gas-contacting area as do the ribs of the other figures, but produce a somewhat greater turbulent action on the gases 20 and air flowing through the flues. In this case, the ends of the ribs 32 of one brick will fit between curved abutting surfaces or seats 33 of adjacent ribs, so that there is a somewhat closer interlocking engagement between the bricks of each course. 25

In Fig. 13, the bricks 34 have protuberances or ribs 35 which are plain on each end and which terminate short of the vertical edges of the bricks, so as to leave unribbed portions 36 at the edges of the bricks, which will fit into the unribbed 30 spaces 37 of adjacent bricks.

Referring now to Fig. 14, I show bricks 38 that are ribbed along their vertical mid portions and are beaded and grooved in their vertical edges at 39, so that the bricks will have interlocking engagement with one another. Intermediate bricks 40 are ribbed similarly to the bricks 38, but have their vertical edges plain, and they fit between adjacent rows of bricks 38. The flue openings 41 formed by the bricks 38 and 40 are of the same 40 general contour as the flue openings in Figs. 4 to 8.

The bricks of Figs. 11 to 14 will be formed with ribs of different depth or thickness, so that the graduated flue zones can be formed thereby, as 45 in Figs. 1 to 8.

I claim as my invention: —

1. Checker structure for furnaces, comprising vertical flues formed of bricks arranged in superposed relation and each having a plurality of 50 vertical ribs so arranged and of such transverse dimensions as to materially increase the wall areas of the flues, compared to flues formed of plane-faced bricks of similar length and width, the ribs on each brick having end-to-end abutting relation with the ribs of vertically adjacent bricks.

2. Checker structure for furnaces, comprising vertical flues formed of bricks arranged in superposed relation and each having a plurality of vertical ribs so arranged and of such transverse 60 dimensions as to materially increase the wall areas of the flues compared to flues formed of plane-faced bricks of similar length and width, the checker structure being divided into zones of graduated cross-sectional flue areas, formed by 65 employing bricks having ribs of different lateral dimensions, and the ribs on the bricks of one zone being disposed in end-to-end abutting relation with the ribs of bricks in an adjacent zone.
